UNITED STATES PATENT OFFICE.

ALFRED WEILAND, OF NEW YORK, N. Y.

CARBURETER.

1,345,098.

Specification of Letters Patent. Patented June 29, 1920.

Application filed January 27, 1919. Serial No. 273,343.

To all whom it may concern:

Be it known that I, ALFRED WEILAND, a citizen of the United States, and a resident of New York, county of New York, and

5 State of New York, have invented certain new and useful Improvements in Carbureters, of which the following is a specification.

Some of the objects of the present invention are to provide means for replenishing the liquid fuel reservoir of a carbureter from a low level tank; to provide means for preventing flooding of the carbureter when the motor is at rest; to provide means for 10 establishing a negative pressure upon a fuel reservoir of a carbureter when the motor is running and to maintain such negative pressure when the motor comes to rest; to provide an auxiliary priming device for a carbureter; and to provide other improvements 15 as will hereinafter appear.

In the accompanying drawings Figure 1 represents a sectional elevation of a carbureter embodying one form of the present invention; and Fig. 2 represents a plan of the same.

Referring to the drawings one form of the invention is shown wherein a carbureter casing 10, of any suitable form or shape is 20 arranged to provide a transverse air passage 11, a carbureting chamber 12, and a main fuel reservoir 13.

For the purpose of feeding liquid fuel to the carbureting chamber 12, the main reservoir 13 has an outlet 14 arranged in a bottom partition 15, by which the fuel is delivered to a storing reservoir 16 below the main reservoir 13. This storing reservoir 16 has an outlet 17, preferably formed by a 25 downwardly converging wall 20 to discharge into a supply or feeding chamber 21, which has a communication by way of a channel 22 with a jet reservoir 23 having a discharge port 24.

40 In order to control the passage of liquid fuel through the outlet 14, a valve 25 is provided having fixed connection with a spindle 26, which has a suitable bearing in a bushing 27 provided with ports 28, where- 45 by the fuel has free flow to the outlet 14. This spindle 26 projects into the main reservoir 13 and has connection with a lever

30 suitably pivoted at 31 and carrying on its other end a float 32, by which variations in the liquid level determine the opening 55 and closing of the valve 25.

For feeding the liquid fuel from the storing reservoir 16 in regulated quantities the outlet 17 is arranged to be sealed and unsealed by the liquid content of the supply 60 chamber 21, this latter having an air vent passage 33 to the exterior of the casing 10, the inner end of which is above the normal liquid level in the chamber 21. Thus as the content of the chamber 21 is depleted, 65 the entering air bubbles upward through the outlet 17 to cause the fuel in the storing reservoir 16 to replenish the supply chamber 21 gradually. When the entering liquid has raised the level in the chamber 21 to a 70 height where the outlet 17 is sealed, further feeding of the chamber 21 ceases. In the normal operation of the carbureter the level in the chamber 21 remains substantially in the plane of the mouth of the outlet 75 so that there is a substantially continuous bubbling through of air and the addition of increments of fuel to the supply chamber 21.

For the purpose of regulating and controlling the fuel to the carbureting chamber 12, the discharge port 24 opens within a cylindrical passage 34 formed by a cylindrical bushing 35 fixed to the casing 10 and forming a support and bearing for the body 80 portion of an oscillatable throttle valve 36, the other end of which has bearing upon a cylindrical stem 37 projecting into the chamber 12. This stem is arranged in spaced relation with the end of the bushing 85 35 to provide a circumferential passage 40 in the plane of a pair of ports 41 and 42 formed in the throttle valve 36 and forming the discharge jet proper. An open ended tube 43 extends from the stem 37, being spaced from the bushing 35 to provide a 90 passage 44 by which air may be directed from the port 41 downwardly through the liquid when the throttle is in closed position and thus serve as an auxiliary priming 95 means. The stem 37 forms a bearing for a reciprocable hollow member 45 carrying on one end a needle valve 46 for regulating the 100 opening of the port 24, and on the other end

a piston 47, which is arranged to normally hold the needle valve 46 open through the medium of a coiled spring 48. The piston 47 is mounted for free sliding movement in a cylinder 50 closed by a cap 51 having ports 52 therein whereby air may enter and pass through the member 45 to exit by way of the port or ports 53, which are normally just below the liquid level in the jet passage 44. That portion of the cylinder 50, on the side of the piston 47 opposite to the air side is in communication with the carbureting chamber 12 by way of the aligned ports 54 and 55. The construction is such that the motor intake pressure directly controls the needle valve 46 so that it opens, partially opens or closes the port 24 in accordance with the load and working conditions of the motor.

20 For the purpose of replenishing the main reservoir 13 from a low level tank by the negative pressure of the motor intake, a conduit 60 is provided which is arranged to establish communication between the main reservoir 13, above the liquid level therein, and the carbureting chamber 12 or any suitable point on the motor side of the throttle valve 36. A pipe 61 from the low level tank (not shown) has its discharge end terminating within and communicating with the main reservoir 13 above the liquid level therein, so that it is subjected to the conditions of negative pressure transmitted by the conduit 60 as a medium.

25 In order to prevent overflow of the liquid fuel by way of the main jet into the carbureting chamber 12, when the motor is at rest and the negative pressure returns to normal, the conduit 60 has its outlet 62 laterally disposed and terminating at a low point of the chamber 12, and adjacent thereto a cupped recess 63 is formed in the floor of the casing 10 to encircle the bushing 35 so that any overflow of liquid fuel will collect in the recess 63. Such collected liquid will effectually seal the opening to the conduit 60, thereby preventing equalization of pressure upon the liquid in the main reservoir 13 and consequently there can be no flooding of the carbureting chamber. The relatively small quantity of collected fuel, due to the temporary overflow, serves also as a priming charge when the motor is again started, and as soon as this is taken up the conduit 60 has its outlet 62 unsealed and working conditions are restored.

30 To admit air to the carbureting chamber 12 by way of the passage 11, the latter is in communication with an air intake pipe 64, preferably subjected to the exhaust or other source of heat, so that the entering air is preheated in the desired manner before entering the carbureting chamber.

35 While the foregoing means for prevent-

ing flooding of the carbureter has been described in connection with one form of throttle valve it is to be understood that this is to be taken as only by way of example and that the device is adapted for use with any type of carbureter, irrespective of the particular throttle valve employed, wherein the fuel is supplied to the main fuel reservoir from a low level fuel supply tank by utilizing the negative pressure of the motor intake.

40 It will now be apparent that a complete, unitary structure has been devised capable of carrying out the ends desired whereby a balance of pressure in the main fuel reservoir is prevented when the motor comes to rest and the negative pressure in the intake is restored to normal. In consequence there can be no overflow to the carbureting chamber by way of the main jet and flooding is entirely prevented. Further the small quantity of liquid, which does overflow to seal the by-pass conduit, forms a convenient puddle to act as a priming charge as soon as the motor is again turned over.

45 Having now described the invention what I claim and desire to protect by Letters Patent is:—

1. The combination of a reservoir, means forming a communication between said reservoir and a chamber subject to the intake pressure of a motor of the explosive type, and means including a liquid seal to prevent flow by gravity from said reservoir when the motor intake pressure is relieved.

2. In a carbureter, the combination of a reservoir arranged to be supplied from a low level source of supply, means to cause said reservoir to be replenished from said source by negative pressure in the motor intake, and means including a liquid seal to prevent a flow by gravity from said reservoir when the motor intake negative pressure is relieved.

3. In a carbureter, the combination of a reservoir arranged to be supplied from a low level source of supply, and a conduit forming a communication between said reservoir and the motor intake, said conduit having an inlet at the motor intake end arranged to be liquid sealed by any overflow of liquid fuel from the carbureter when the motor is at rest.

4. In a carbureter, the combination of a reservoir arranged to be supplied from a low level source of supply, a conduit forming a communication between the said reservoir and the motor intake, said conduit having an inlet at the motor intake end arranged to be liquid sealed by any overflow of liquid fuel from the carbureter when the motor is at rest, and means adjacent said inlet to collect said overflow to form a priming charge.

5. In a carbureter, the combination of a casing forming a reservoir and a carbureting chamber, means forming a passage for liquid fuel from said reservoir to said chamber, said casing having a recess below the point of discharge of said passage, and a conduit between said chamber and said

reservoir, said conduit having an inlet within said recess.

Signed at Philadelphia, in the county of 10 Philadelphia and State of Pennsylvania, this 16th day of January, A. D. 1919.

ALFRED WEILAND.
